DESIGN FOR WALL-PAPER.

Design No. 12,542, dated October 25, 1881.

UNITED STATES PATENT OFFICE.

EDUARD LEISSNÉR, OF NEW YORK, N. Y., ASSIGNOR TO LEISSNÉR & LOUIS,
OF SAME PLACE.

DESIGN FOR WALL-PAPER.

SPECIFICATION forming part of Design No. 12,542, dated October 25, 1881.
Application filed August 25, 1881. Term of patent 3½ years.

To all whom it may concern:

Be it known that I, EDUARD LEISSNÉR, of New York, in the county and State of New York, have invented a new and original Design for Wall-Paper, of which the following is a specification.

This invention relates to a new and original design for wall-paper and similar fabrics; and it consists in the novel grouping and configuration of parts, hereinafter more fully described.

The accompanying photograph illustrates a face view of a wall-paper having my new design.

F is the upper border, and G the lower border, of the wall-paper. Between these two borders is the principal portion H. The border F is made of two interlocking bars or lines bent alternately up and down, leaving spaces for a row of beads, j. The border G is composed of series of interlocking bars k and h, of which some enter into the ornamentation of the main body H of the wall-paper, forming an upright post, g, and branching to the right and left at the bottom of the border F. To this post g is joined the ornamental outline for the figures D D. Each of these figures D D con-

tais an inner floral group, d, and conventional leaves e on top and lower scroll, i, as shown. The post g is ornamented by a pine-apple-shaped figure near its center, and has branches f with conventional leaves at its sides.

I claim—

1. The design for wall-paper, consisting of the border F, having beads j, substantially as shown.

2. The design for wall-paper, consisting of the border G, having bars k and bars h, said bars forming also the post g, and branching to the right and left at the bottom of the border F, and of the ornamental outline of the figures D, and of said figures D, having ornaments d e i, and of the ornaments f, substantially as shown.

3. The design for wall-paper, consisting of the border F, having beads j, border G, having bars k and h, figures D D, having ornaments d e i, post g, and ornaments f, substantially as shown.

EDUARD LEISSNER.
